UNITED STATES PATENT OFFICE.

JAMES HARRY THOMPSON, OF TRENTON, NEW JERSEY.

IDENTIFICATION DEVICE.

997,342.

Specification of Letters Patent. Patented July 11, 1911.

Application filed July 20, 1910. Serial No. 572,922.

To all whom it may concern:

Be it known that I, JAMES HARRY THOMPSON, citizen of the United States, residing at Trenton, in the county of Mercer and 5 State of New Jersey, have invented new and useful Improvements in Identification Devices, of which the following is a specification.

My present invention pertains to identification devices for business transactions, and 10 more particularly to the kind of such devices which comprise a picture of the party to whom the device is issued.

The object of my invention is to provide 15 an identification device having a wide range of usefulness, and embodying such a construction that the picture of the holder is protected against injury and alteration and cannot be removed for the substitution of a 20 spurious picture without such fact being plainly manifest.

Other advantageous characteristics of the invention will be fully understood from the 25 following description and claim when the same are read in connection with the drawings, accompanying and forming part of this specification, in which:

Figure 1 is a perspective view illustrating my novel device as open and as carrying 30 a railway mileage ticket. Fig. 2 is a detail perspective view showing one mode of attaching a ticket to the device. Fig. 3 is a section on line 3—3 of Fig. 1. Fig. 4 is a section on line 4—4 of Fig. 1. Fig. 5 is a 35 plan of the transparent picture retainer and protector. Fig. 6 is a detail view showing another manner in which a ticket can be detachably connected to the device.

Referring by letter to the said drawings, 40 and more particularly to Figs. 1 to 5 thereof: A is a railway mileage ticket provided with a tongue *a* and designed when sold to be given an individual number and to receive the signature of the purchaser, as 45 shown in Fig. 1, and B is the body of my novel identification device. The said body B is preferably, though not necessarily, in the form of a folder—*i. e.*, comprises flaps *b* and *c* flexibly joined together at *d*, and 50 the flap *b* is provided in its inner side with a socket *e* to receive the tongue *a* of the ticket, while the flap *c* is provided with a pocket *f*, Fig. 3, designed to receive cards

and other small articles. When desirable the tongue *a* on the ticket and the socket *e* 55 in the body may be dispensed with, and the ticket provided with a male fastener *a*² and the body with a female fastener *e*² as shown in Fig. 6, or the ticket may be attached to the body in any other approved manner 60 without involving departure from the scope of my invention as claimed.

The folder flap *c* is provided in its inner layer *g* with slits *h* *i* and *j*, and at the time of issue is given a number corresponding to 65 that of the ticket and is provided at one or more (preferably two) places with the signature of the purchaser, as shown.

The picture *l* of the purchaser is furnished by that party at the time of purchase, and after being stamped or otherwise authenticated on its face by the proper railway official, so that the authentication will be displayed, is placed against the face of the flap *c* and between the slits *h* *i* and *j*. 70 Then the picture retainer and protector *m*, which is a piece of suitable transparent material such as celluloid, mica or the like, is placed over the picture, and the lower and side edges of the said retainer and protector *m* are disposed in the slits *h* *i* and *j*, after which seals *n* or other suitable securing means are affixed to the folder flap *c* 75 of the body and to the retainer and protector *m* by adhesive or in any other approved manner, and are stamped in the manner illustrated or in any other approved manner to show their genuineness. With 80 the picture covered and protected and secured in position in the manner illustrated 85 and described, the picture is preserved and alteration thereof is precluded, and in the event that it is attempted to substitute a spurious picture for the original, the seals *n* 90 will be so affected that the fraud will be detected when the picture and device as a 95 whole is subjected to even casual scrutiny.

In the use of my novel device, it will be observed that identity is established between the ticket, the device and the holder 100 of the latter, and that the device may be used repeatedly to connect the individual with a railway ticket or to establish the genuineness of the particular party by whom the device is carried. It will also be 105 observed that when used in connection with

a railway ticket, the device obviates the necessity of the conductor requesting samples of the signature of the party.

When deemed expedient the conditions 5 governing the use of the device may be printed on the device or the ticket used in connection therewith or both.

While I have shown and described one form of my invention, it is to be understood that I am not limited to the details or the form or relative arrangement of parts disclosed, but that modifications may be made therein, within the scope of the appended claim without departing from the 15 spirit thereof. For instance the folder form of the body B does not constitute part of my invention, inasmuch as the body may be of any character consonant with the purpose of my invention and suited for use with a 20 number of different certificates, tickets or the like or alone as a mere identification device.

Having described my invention, what I

claim and desire to secure by Letters-Patent, is:

An identification device, comprising a body having in one side a slit and other slits spaced apart and extending at right angles to the first-named slit, a picture placed against the side of the body and between the said slits, a transparent retainer and protector arranged in front of the picture and having edge portions disposed in said slits and also having an edge portion disposed against the side of the body, and authenticated seals affixed to the side of the body and the retainer and protector, substantially as and for the purpose specified.

In testimony whereof I have hereunto set my hand in presence of two subscribing 40 witnesses.

JAMES HARRY THOMPSON.
